UNITED STATES PATENT OFFICE.

WILLIAM M. CROSSWHITE, OF SNOW LAKE, ARKANSAS.

COMBINED WALL BLACKBOARD AND WRITING DESK.

Application filed August 22, 1923. Serial No. 658,783.

To all whom it may concern:

Be it known that I, WILLIAM M. CROSSWHITE, a citizen of the United States, residing at Snow Lake, in the county of Desha 5 and State of Arkansas, have invented a new and useful Combined Wall Blackboard and Writing Desk, of which the following is a specification.

This invention relates to a combined wall 10 blackboard and writing desk, and is more especially a continuation in part of my application filed May 24th, 1923, Serial No. 641,271.

One of the objects of the invention is to 15 provide a structure of this character constituting an attractive article of furniture and which has a combined desk and container that can be supported readily in either of two positions for use either as a desk or as a paper 20 holder or the like.

A further object is to provide a novel arrangement of pockets or compartments for holding various articles useful in connection with a desk and blackboard.

25 A still further object is to provide a structure utilizing a blackboard, which, when not in use, can be turned facing the wall, the back of the blackboard being provided with a mirror and any suitable means such as a 30 picture, adding to its attractiveness.

With the foregoing and other objects in view which will appear as the description proceeds, the invention resides in the combination and arrangement of parts and in 35 the details of construction hereinafter described and claimed, it being understood that changes in the precise embodiment of the invention herein disclosed may be made within the scope of what is claimed without departing from the spirit of the invention.

40 In the accompanying drawings the preferred form of the invention has been shown.

In said drawings—

45 Figure 1 is a perspective view of the device.

Fig. 2 is a front elevation showing the blackboard in position for use.

Fig. 3 is a section on line 3—3, Fig. 2.

50 Referring to the figures by characters of reference 1 designates a base having an upstanding frame 2 at the back thereof and which frame is preferably supported by means of beams 3 or the like connected to an eye 4 located at the center of the top of the frame. These beams diverge upwardly

and are supported by pulleys 5 from which the same extend downwardly along the sides of the frame 2 through guide loops 6 extending from the frame. Weights 7 are attached to the lower ends of the chain. Pins 60 6' extend from the frame and are detachably engaged by the chain. By pressing upwardly against the bottom of the base 1 the chain 3 can be released from pins 6' and the structure adjusted upwardly or downwardly after which the chain is again placed on pins 6' and thus anchored. The weights 65 act as counter-balances for facilitating the adjustment of the structure.

The inner frame 8 is mounted for rotation in the main frame 2 about pivot pins 9 in the top and bottom of the frame 2. This frame 8 is provided with a blackboard 10 and arranged back of the blackboard is a mirror 11 and a picture 12. A pin 13 can 70 be provided for holding the frame 8 against rotation. Obviously by removing this pin the frame 8 can be revolved to bring the blackboard 10 to position in front of the structure or if preferred, the blackboard can 75 be brought to position facing the wall, thereby closing the mirror 11 and the picture 12.

The beam 1 projects forwardly a greater distance at the bottom thereof than at the top and the upper portion 13 of the base is 80 provided with a bottom 14 and a front wall 15, thus forming a compartment 16 extending throughout the width of the base. The lower portion of the base projects forwardly 85 beyond the wall 15 and is provided with superposed partitions 17 and 18 and a front 90 wall 19. This wall 19 is located above the partition 18 and cooperates therewith to form a compartment 20. A drawer 21 is 95 slidably mounted between the partitions 17 and 18.

Pivottally connected to the sides of the base 1 are hangers 22 the lower ends of which form the sides of a holder 23 extending throughout the width of the base and divided by partitions 24 into separate compartments 25. These compartments are adapted to hold writing paper, envelopes and the like, and the front wall of the holder 23 is extended downwardly below the 105 holder as indicated at 26.

When it is desired to use the structure as a writing desk the holder 23 is swung upwardly to the position indicated by broken lines in Fig. 3, after which the drawer 21 is 110

5 pulled forward so as to extend under and support the holder 23. Thus the wall 26 of the holder can be used as a desk. By pushing the drawer 21 inwardly, the holder 23 will gravitate to the position shown in Figs. 1 and 2.

10 Drawer 21 and the compartments 16 and 20 can be used for holding various articles such as books, chalk, erasers, etc.

15 Prop projections 27 are extended laterally from the base 1 so as to limit the swinging movement of the holder 23 in one direction.

What is claimed is:—

1. A device of the class described including a base, an integral frame upstanding therefrom, said base having superposed compartments, the lower compartments being extended forwardly beyond the upper compartments, counterbalanced means for supporting the frame and base, a holder pivotally connected to and normally suspended beneath the base, and a drawer in the base and slidable under the holder to support the

holder in a forwardly extended position in front of the base.

25

2. A device of the class described including an adjustably supported structure comprising a frame and a base below and integral with the frame, said base having superposed compartments, a holder pivotally connected to and normally suspended under the base and having separate compartments, said holder being movable to forwardly extending position in front of the base with the front wall of the holder constituting stops thereof to provide a writing desk, and a drawer in the base movable to position under the holder to be supported in forwardly extending position.

30

35 In testimony that I claim the foregoing as my own, I have hereto affixed my signature in the presence of two witnesses.
